(57) **CLAIM**

The ornamental design for a display screen with an HVAC graphic user interface for an automotive vehicle, as shown and described.

DESCRIPTION

FIG. 1 is a front view showing a first view of a display screen with an HVAC graphic user interface for an automotive vehicle, of our new design; and,

FIG. 2 is a front view showing a second image thereof. The outermost broken line rectangle shows the display screen, and forms no part of the claimed design. The broken lines are for illustrative purposes only and form no part of the claimed design. The subject matter in this patent includes a process or period in which an image changes to another image, in response to a user selection. The appearance of the transitional image sequentially transitions between the images shown in FIGS. 1 and 2. The process or period in which one image transitions to another image forms no part of the claimed design.
